UNITED STATES PATENT OFFICE

ADOLPHUS MAYER, OF WASHINGTON, DISTRICT OF COLUMBIA

CENTRIFUGAL SWITCH

Application filed July 31, 1926. Serial No. 126,321.

This invention relates to improvements in speed governors for electrically driven motors, and has for its object to provide a self-contained electrical speed governor by the use of which friction is eliminated in its functioning parts and at the contact points of the circuit make and break device.

It is a further object to so construct the device that the usual end shake of the armature shaft has no influence on the make and break points, or gap when functioning and to this end it is proposed to mount the governor in such a manner that it will virtually form an integral rotating part of the rotary element of the motor assembly.

With the foregoing and other objects in view, the invention consists in the combination of parts and in details of construction hereinafter set forth in the ensuing specification and appended claim, certain embodiments being illustrated in the accompanying drawings, in which:

Figure 1 is a side elevation, partly in section of the governor as applied to the rotary shaft of an electric motor;

Figure 2 is a view in detail of the centrifugal weight units;

Figure 3 is a sectional view taken along line 3—3 of Figure 1;

Figure 4 is a detailed view in front elevation of the insulating block;

Figure 5 is a detailed view in front elevation of the metal plates.

Referring more particularly to the drawings, there is shown a fragmentary portion of an electrical motor *p* having an armature shaft *a*. In the usual type there is a considerable end-shake between its armature bearings. However, in the present case, there is mounted on this shaft *a* a metal sleeve *b* insulated from the shaft by an insulating sleeve *e*. The portion of larger diameter of sleeve *b* has recesses *d* arranged in its periphery, as shown in detail in Figure 3, for the insertion and fixed mounting at its extremities of a spring *h* forming a loop to which are secured along this loop centrifugal weights *f*.

Suitably mounted on the armature shaft *a* is an insulating block *g* carrying posts *i* and threaded plates *l*. A washer *m* is arranged

between the plates *l* which are secured to the posts *i*. The block *g*, posts *i*, plates *l*, and washer *m* form an integral unit which revolves with the armature shaft as a unit. The threads in the plates *l* are formed in such a manner as to not precisely match in order to produce a stiffness against automatic change of position of the adjustable contact screw *n*. One of the plates may also be springy to produce the same result, or a lock nut or any other suitable arrangement could be used for this purpose.

The other contact point is located at the apex of the spring *h*. Contact springs *c*, bearing against the sleeve *b* and a similar pair against the unthreaded end of the adjustable contact screw *n*, carry the current to the two make-and-break speed regulating contact points at *k*.

When the armature shaft, and the assembly connected thereto rotates, the centrifugal force on the weights *f* produces a recession from, or approachment of the contact points in a rectilinear and axial direction, and a consequent release or engagement of the contact carried by the spring *h* with the adjustable contact screw *n*, according to the variance in speed of the motor driven shaft *a*. Adjustment of the contact screw *n* thus respectively accelerates or retards the speed of the armature, according to the setting of the contact screw *n*.

Speed regulating, motor driving circuit is such that when the motor is at rest, contact points *kk* are closed, allowing passages of driving current and starting the motor. From a suitable generator, dynamo or battery *s* a lead from one pole goes directly to the motor. The other pole is connected to one pair of contact springs *c*, passing current thru *kk*, governor springs *h*, hub *b*, other pair of contact springs *c*, to the motor. A suitable resistance is shunted across *kk*. If on switching on current, the motor runs too slow, it shows that the generator is deficient and therefore not suitable. If the motor runs too fast, the weights *f* will cause a break of current at *k*, and the current to the motor will now be furnished through *R* only, which is not sufficient, and points *kk* will again make

contact. On retracting the contact screw *n*, or advancing it, if too much retracted, the make-and-break is so regulated that the desired speed of the motor is obtained.

- 5 By reason of the fact that both contacts of the circuit make-and-break device are mounted so as to rotate in unison with each other and the armature shaft, there is no possibility of friction being produced in their contacting
- 10 with each other. The elasticity of the spring *h*, acted upon by the centrifugal force created by the rotating weights *f*, produces the only motion employed to make or break the speed controlling contacts.
- 15 Furthermore, the usual end-shake of the armature has no influence on the make-and-break contacts as both rotate and move with the shaft, being virtually integral parts thereof.
- 20 Having thus described my invention, I claim:

An automatic electrical speed regulator for an electrical motor, said regulator being fixedly mounted on a rotary element of said motor

- 25 and adapted to rotate with said element and comprising a make-and-break device arranged in the motor driving electrical circuit, said device employing a plurality of loop springs with peripherally arranged weights
- 30 and a contact point attached to the apex of said loops, and thus freely suspended with relation to said rotary element, the other contact being adjustably mounted independently of, outside of and in proximity to said first
- 35 contact which is centrifugally operable by means of said weights to cause rectilinear movement of the contact carried thereby, said device being so arranged as to rotate as a unit for the purpose of maintaining a constant
- 40 contact gap independent of end thrusts present within the rotary element.

In testimony whereof I affix my signature.
ADOLPHUS MAYER.
